UNITED STATES PATENT OFFICE.

JOEL B. LOW, OF SAN FRANCISCO, CALIFORNIA.

ROCK-CRUSHER.

SPECIFICATION forming part of Letters Patent No. 393,440, dated November 27, 1888.

Application filed May 16, 1888. Serial No. 274,070. (No model.)

To all whom it may concern:

Be it known that I, JOEL B. LOW, of the city and county of San Francisco, State of California, have invented an Improvement in Rock-
5 Crushers; and I hereby declare the following to be a full, clear, and exact description of the same.

My invention relates to that class of rock-crushers in which the rock is crushed between
10 opposing jaws; and my invention consists in the constructions and combinations of devices which I shall hereinafter fully describe and claim.

The object of my invention is to provide a
15 simple and effective rock-crusher which can be easily operated and adjusted to crush the rock to any degree of fineness, and which can be readily cleaned in all its parts, making it especially adapted for the use of assayers and for
20 any small work where samples are desired.

Referring to the accompanying drawings for a more complete explanation of my invention, Figure 1 is a vertical section of my rock-crusher, showing the jaws in working position. Fig. 2 is a side elevation showing the jaws elevated out of the way, the hopper E being removed to permit the jaw B to be raised.

A is the frame of the machine, consisting of separated side pieces or standards and a base. B is the stationary jaw, which is secured at
30 its upper end between the sides or standards of the frame by a bolt, b, and its lower end is held to its place or seat by means of a removable pin or bolt, b'.

C is the moving jaw, having a long stem or leg, c, extending upwardly between the separated sides of the main frame and provided with a head, c', which fits over the operating-eccentric d of the drive-shaft D. This eccentric
40 is located in the central vertical plane of the space between the jaws, so that the lower edges of the two jaws would naturally come in contact. The lower end or working portion of the jaw C opposes the working-surface of the
45 stationary jaw, forming between the two jaws a tapering space, into which the material is fed by means of a small removable hopper or chute, E, let into the side of the frame above the top of the stationary jaw. This space between the jaws is regulated to vary the fineness to which the material is crushed by the following means:

Pivoted to the back of the base of the moving jaw at f is an arm, F, the free end of which has a lug, f', to which is pivoted a link, G, the free end of which fits in a slotted or grooved bearing, H, on the main frame, and is provided with a spring buffer or cushion, g, behind the fixed bearing H, and held or set up by a nut, g', on the end of the link. This is the take-up for the moving jaw, holding its base or operating portion away from the other jaw to permit the discharge of the material and to
55 primarily adjust the space between the jaws.

Threaded through the fixed bearing H is an adjusting-screw, I, the end of which bears against the end of the arm F in a small socket made therein for the purpose. By setting up this screw the moving jaw is pressed closer to the stationary jaw, so as to increase the fineness of the crushing, and by turning the screw back the spring-buffer g pulls the jaw outwardly to increase the space between the two jaws and provide for coarser crushing.

Near the top of one side of the frame are made extension lugs or hooks J, which serve the following purpose: By taking out the removable bolt or pin b', which holds the stationary jaw B in place, said jaw may be grasped from behind and turned around on its bolt b above, as a pivotal center, to an almost vertical position at the top of the frame, with its face turned outwardly; and in this position it is held by placing the bolt or pin b', which was removed from below, in the extension lugs or
75 hooks J just in front of the jaw. Instead of these lugs for holding the bolt, it is obvious that I might make holes through the frame to receive the bolt, in order to hold the jaw in its elevated position. Now, by running back the
80 adjusting-screw I, so as to free the arm F, the link G may be raised from the slotted or grooved bearing H, and the moving jaw C may be turned around on the eccentric d as a center to a position a little beyond the vertical,
85 in which position it rests against the back of the other jaw with its own face outward. It will now be seen that when both jaws are turned to an elevated position their operating-faces are exposed and may be thoroughly
90 cleaned, and the whole interior of the frame and mortar is clear, and may be cleaned out by sweeping without the least inconvenience.

Having thus described my invention, what I

claim as new, and desire to secure by Letters Patent, is—

1. In a rock-crusher, the frame, the moving jaw pivoted above, and a stationary jaw opposing said moving jaw, in combination with the take-up for the base of the moving jaw, consisting of the pivoted arm having the lug f' , the link connected therewith and having a buffer or cushion on its end, a slotted or grooved bearing, into which said link drops, whereby it may be readily released when the moving jaw is to be turned to an elevated position out of the way, and the screw bearing against the end of the arm, substantially as 15 herein described.

2. In a rock-crusher, and in combination with a frame, the stationary jaw pivoted at its top in the frame, whereby it may be turned up, when released, to an elevated position, a removable bolt or pin behind the stationary jaw for holding it in its working position and adapted to be placed in the frame in front of it to hold it when in an elevated position, and the moving jaw pivoted by its top in the frame, 20 and adapted to be turned up to an elevated position and rested against the other jaw, substantially as and for the purpose herein described.

3. In a rock-crusher, and in combination

with a frame, a stationary jaw pivoted at its top in said frame, whereby it may be turned up to an elevated position, a removable pin or bolt for holding the jaw in a working position and in an elevated position, a moving jaw in the frame, and a driving-eccentric fitted in the head of the moving jaw for operating it, and on which said jaw may be turned to an elevated position to rest against the other jaw, substantially as and for the purpose herein described.

4. In a rock-crusher, the frame having on one side the lugs or hooks J , in combination with the stationary jaw pivoted at its top in the frame and adapted to be turned up to an elevated position, as described, the removable bolt or pin passing through the frame behind the jaw to hold it in its working position, and adapted to be placed in the lugs or hooks J in front of said jaw to hold it in its elevated position, and the pivoted moving jaw adapted to be turned up to an elevated position and rest 40 against the other jaw, substantially as and for the purpose herein described.

In witness whereof I have hereunto set my hand.

JOEL B. LOW.
